MACHINE FOR APPLYING PRESSURE TO
SHOE BOTTOMS

Royal G. Madan, Stoughton, Mass., assignor to
United Shoe Machinery Corporation, Borough
of Flemington, N. J., a corporation of New
Jersey

Application August 15, 1939, Serial No. 290,324

17. Claims. (Cl. 12—38)

This invention relates to machines for applying pressure to shoe bottoms, for example, in the cement-attaching of soles to shoes, and particularly to pads and pad boxes for use in such machines.

5 Objects of the invention are to provide a pad and a pad-supporting box which are capable of quick and accurate adjustment to cause the pressing surface of the pad to assume the longitudinal contour of the bottom of a shoe irrespective of 10 the height of the heel which the shoe is designed to have.

As illustrated, a hollow pad of molded rubber is provided, the pad being initially formed with a top surface adapted to fit the bottom of a shoe 15 which is to have a heel of medium height. A pad so molded and filled with water is well adapted to be bent farther along the location of the ball line to accommodate a higher heel or to be flattened so as to accommodate a lower heel. 20 the bottom and sides of the pad are supported by a box the forepart of which is movable about a fixed transverse axis located vertically about half way of the height of the pad and substantially beneath the ball line of a shoe placed on the pad. 25 25 The shank portion of the pad rests on a shank support forming the bottom of the rear portion of the pad box, which shank support is adjustable about a pivot extending transversely of the box and located beneath the pivot of the forepart of 30 the box. The rear part of the pad is supported by means movable heightwise of the box and extensibly connected to the rear end of the shank support. Means is provided for effecting accurate heightwise adjustment of the rear part of 35 the pad support comprising a toggle and a right and left-hand screw for operating the toggle. When adjusted heightwise, the support for the rear end of the box carries with it the rear end of the shank support. Similar means is provided 40 for adjusting the forepart of the box about its pivot and, by operating the two adjusting means, the contour of the pressing surface of the pad may be changed to correspond substantially to 45 the longitudinal contour of any shoe bottom.

These and other features of the invention will appear more fully from the following description when read in connection with the accompanying drawings and will be pointed out in the 50 appended claims.

In the drawings,

Fig. 1 is a side elevation, partly in section, of a pad and pad box embodying the present invention, the extreme toe portion of the pad and 55 box being broken away;

Fig. 2 is a plan view of the pad box, the end portions being omitted;

Fig. 3 is a detail in side elevation of the rear end of the box;

Fig. 4 is a front elevation of means for adjusting the forepart of the box;

Fig. 5 is an exploded view of the pad-supporting and adjusting means at the rear end of the box; and

Fig. 6 is a rear elevation, partly in section, 10 showing the means for adjusting the rear end of the box.

A pad box embodying the present invention, as illustrated in Fig. 1, comprises a base 10 adapted to be secured to the pad box support of a machine 15 of the type disclosed in Letters Patent of the United States No. 2,047,185, granted July 14, 1936, upon application of Ballard et al. The rear part of the base is formed with a rear wall 12 and two side walls 14, 16 which embrace the rear portion 20 of a pad 18. The pad 18 is preferably a water pad, that is, a hollow rubber vessel filled with water. The hollow pad is molded of rubber, the top or pressing surface of the pad being reinforced by layers of canvas 20. As initially molded, 25 the pad preferably has a pressing surface of a contour to fit a shoe bottom which is to have a heel of medium height, for example an 18/8 heel, i. e., a heel two and a quarter inches in height. A pad thus molded can be flattened to accommodate the bottoms of shoes which are to have lower heels and can be bent farther to conform to the bottoms of shoes that are to have higher heels without straining unduly either the top or the bottom layers of the pad. In changing the 30 longitudinal contour of the pad to correspond to the longitudinal contours of different shoe bottoms, it should be bent about a transverse axis located substantially beneath the ball line of the shoe. To this end the forepart of the pad 18 is 35 enclosed in a forepart box having side walls 22 and 24, a bottom wall 26 and a front wall 27 (Fig. 4) at the toe end of the pad. The side wall 22 is pivoted to the side wall 14 of the rear part of the box by a pivot stud 28 held in place 40 by a screw 30, the side wall 24 being similarly pivoted to the rear side wall 16, the axes of the pivots, of course, being in transverse alignment and located between the top and bottom walls of the pad 18. As shown, the pivots are approxi- 45 mately midway between the top and bottom walls of the pad.

To adjust the forepart of the box up and down about the fixed pivots 28, the mechanism shown in Figs. 1 and 4 is provided. A bar 32 is pivoted 50

at each end by a pivot 34 to an ear 36 projecting downwardly from the bottom of the forepart of the box. At the center of the bar 32 is a pivot pin 38 which passes through the bar and through 5 adjacent ends of two pairs of links, one pair 40, 42 being located on the front side of the bar and the other pair 44, 46 (Fig. 1) on the rear side of the bar. The free ends of the links 42, 46 are pivoted to studs 48 projecting from opposite sides of a block 50 which is tapped to receive a threaded portion 52 of a rod 54. The free ends of the links 40, 44 are similarly pivoted at 56 to a block 58 tapped to receive a threaded portion 60 of the rod 54. The threaded portion 60 has a right-hand thread and the threaded portion 52 has a left-hand thread so that when the rod 54 is turned by a hand-wheel 62 the toggle formed by the links 40, 42 on one side of the bar 32 and the toggle formed by the links 44, 46 on the rear side of the 10 bar will be bent and straightened to raise and lower the front portion of the pad box about its pivot 28. The amount of elevation of the front end of the pad box is indicated by a scale 64 adjustably secured to the pad box by screws 65 which pass through slots in the scale. An index finger 66 fixed at 68 to the base 10 cooperates with 15 graduations on the scale 64 to indicate the heel height for which the forepart of the pad is adjusted. For convenience in assembling, the rod 30 54 is preferably mounted for rotation in upwardly open notches 70 formed in the base 10 and is retained in place by screws 72 having conical ends extending into the notches 70 above it. The bottom of the shank portion of the box is formed by 20 a shank-supporting plate 74 pivoted at its front edge by screws 76 which are threaded through ears 78 formed on the base 10. The joint between the bottom 26 of the forepart of the box and the plate 74 is covered by a thin plate 80, the plate 40 being secured to the bottom 26 by screws 82 and having its ends upturned at 84 (Fig. 5) to cover the joint at 28 between the front and rear parts of the box. The rear edge of the plate 80 engages a rabbet 86 on the plate 74, sufficient clearance being allowed between the edge of the plate 80 and the rabbet 86 to permit movement of the forepart of the box about the pivot 28 and of the shank-supporting plate 74 about the pivot 76. The shank plate 74 is preferably upwardly 45 convex longitudinally of the pad and carries at each side a plate 88 having at its lower end a pivot stud 90 which enters a hole 92 in an ear 93 projecting downwardly from the plate 74 and located about midway of the length of the plate. 50 To the upper ends of the plate 88 are attached by screws 94 partial mask plates 96 which extend inwardly over the pad and its cover, if a cover is employed, and serve to hold the pad in place on the plate 74 as it is adjusted about its pivot 76. 55 To the rear end of the shank plate 74 is pivoted a plate 98, the plate 74 having ears through which screws 100 pass and enter the plate 98. The plate 98 is slotted at 101 to receive screws 102 by which it is slidingly secured to a vertically movable heel plate or support 104. The heel plate 104 has downwardly extending ears 106 to which a casing 108 for the rear end of the pad is secured by screws 110, the screws 110 passing through countersunk holes 112 in the casing 108 and being threaded into the ears 106. The casing 108, as shown in Fig. 5, has side, rear and bottom walls to receive the rear end of the pad 18 and flanges 114 which extend over the top of the pad at the two sides. The casing 108 thus serves to con-

nect the rear end of the pad 18 to the vertically adjustable plate 104.

For moving the plate 104 up and down, means similar to that for raising and lowering the forepart of the box is provided. A block 116 is secured by screws 118 to the bottom of the plate 104 and to the block 116 are pivoted by a pin 120 the adjacent ends of two pairs of links, one pair 122, 124 (Fig. 5) having their opposite ends pivoted to blocks 126, 128 by studs 130, 132, respectively, and 10 the other pair of links 134, 136 (Fig. 6) having their free ends secured, respectively, to similar studs 130, 132 on the rear side of the blocks 126, 128. The block 126 is tapped to receive a left-hand threaded portion 138 of a rod 140 and the 15 block 128 is tapped to receive a right-hand threaded portion 142 of the rod 140, the rod being mounted for rotation in the front side wall 14 and in a bearing 143 secured to the rear side wall 16 of the pad box. This rod is arranged to be 20 turned by a hand-wheel 144 to raise and lower the plate 104. For convenience in assembling, the bearing 143 (Fig. 6) is formed in a separate member 145 secured at 147 to the rear wall 16. When the plate 104 is thus raised or lowered, the 25 plate 98 is carried up and down with it and, since the plate 98 is pivoted at 100 to the shank-supporting plate 74 which turns about the fixed pivot 76, the plate 98 shifts forwardly and rearwardly slightly as permitted by the slots 101 which loosely 30 engage the screws 102. To indicate the amount of up-and-down motion of the rear end of the pad as the hand-wheel 144 is turned, an index finger 146 (Fig. 3) is attached at 148 to the casing 108 and cooperates with a scale 150 adjustably secured by screws 152 which pass through slots in the scale 150 and are threaded into the wall 16 of the pad box.

Preferably a cover 154 is provided for the pad 18, the cover being retained in place (Fig. 2) by 40 the usual mask plates and by clips 156 attached to the sides of the forepart of the box and extending inwardly over the edges of the cover 154. At the rear end of the box a plate 158 underlying the cover 154 is secured at 160 to the 45 top end of a vertical slide 162 with which pad boxes of this type are usually provided, the slide carrying the usual mechanism for locating the rear end of the shoe and sole. Side extensions 164 of the plate 158 are turned up over the cover 50 154 to hold its rear end in place and cause it to be moved up and down with the vertical slide 162.

In use, all the adjustments of the pad to adapt it for attaching soles to shoes that are to have heels of any usual height may be made by turning 55 independently or together the two handles or wheels 62, 144. With the illustrated mechanism, turning of these hand-wheels toward each other, that is, turning the hand-wheel 62 to the right and the hand-wheel 144 to the left, will 60 raise the forepart of the pad about its fixed center 28 and will raise the rear part of the pad vertically, causing the shank-supporting plate 74 to turn about its fixed center 76, the amount of adjustment being indicated by movement of 65 the scale 64 with respect to the index finger 66 for the forepart and by movement of the index finger 146 with respect to the scale 150 for the rear part. Supposing a shoe that is to have a heel one inch high is to have its sole attached, 70 the hand-wheels 62, 144 would be turned as described until each of the index fingers 66, 146 is opposite the numeral 8 on its respective scale. The scales 64, 150 are calibrated by adjusting the pad so that its longitudinal contour corresponds 75

successively to a series of lasts having successively higher heels and marking the position of the index finger on the scales after each adjustment. When lasts of a different style are used, 5 it may be necessary to shift the scales heightwise slightly to obtain proper scale readings. This can be effected readily by loosening the screws 65 holding the scale 64 and the screws 152 holding the scale 150 and adjusting the scales 10 up or down as required and then tightening the screws. Thereafter the graduations will indicate the proper adjustment of the pad for a series of lasts of that style and which are to have heels of different height.

15 Having thus described my invention, what I claim as new and desire to secure by Letters Patent of the United States is:

1. Apparatus for use in applying pressure to shoe bottoms comprising a relatively thick pad 20 of yielding material, a support for the forepart of the pad movable about a fixed transverse axis located beneath the ball portion of a shoe placed upon the pad and approximately midway of the thickness of the pad, a toggle connected to the 25 forepart support, and screw means for operating the toggle to move the forepart support about said axis to vary the longitudinal contour of the pad.

2. Apparatus for use in applying pressure to shoe bottoms comprising a relatively thick pad 30 of yielding material, a support for the forepart of the pad movable about a fixed transverse axis located beneath the ball portion of a shoe placed upon the pad and approximately midway of the thickness of the pad, and means comprising a 35 toggle and a right and left hand screw for operating the toggle to move the forepart support about said axis to vary the longitudinal contour of the pad.

3. Apparatus for use in applying pressure to 40 shoe bottoms comprising a relatively thick pad of yielding material, means for supporting the forepart of the pad, means for supporting the shank part of the pad, means for supporting the heel part of the pad, means for adjusting the 45 forepart of the pad about a fixed center located midway of the thickness of the pad, means for adjusting the support for the shank of the pad about a fixed center located below the lower side of the pad, and means for indicating to the operator the amount of adjustment given to the 50 forepart support and to the shank support.

4. Apparatus for use in applying pressure to 55 shoe bottoms comprising a thick pad of yielding material, means for supporting the forepart of the pad, means for supporting the shank part of the pad, means for adjusting the forepart of the pad about a fixed center located midway of the thickness of the pad, means for adjusting the 60 shank support about a fixed center located below the lower side of the pad, and separate means for indicating to the operator when equal amounts of adjustment have been given respectively to the forepart support and the shank 65 support.

5. Apparatus for use in applying pressure to 70 shoe bottoms comprising a relatively thick pad of yielding material, a support for the shank and rear part of the pad movable about a transverse axis, a support for the forepart of the pad movable about a transverse axis located beneath the ball portion of a shoe placed upon the pad and approximately midway of the thickness of the pad, means for adjusting the forepart support 75 about said axis, and means for adjusting the

shank support about a separate axis to vary the longitudinal contour of the pad.

6. Apparatus for use in applying pressure to shoe bottoms comprising a pad of yielding material, a box enclosing an end portion of the 5 pad, a support in said box for the shank portion of the pad, mask plates extending over opposite sides of the shank portion of the pad, means for pivotally connecting said mask plates to the shank support, and means for adjusting the 10 shank support heightwise of the box.

7. Apparatus for use in applying pressure to shoe bottoms comprising a pad of yielding material, a box enclosing an end portion of the pad, a support in said box for said end portion, means 15 for adjusting said support heightwise to vary the longitudinal contour of the pad, and a casing embracing the end portion of the pad, said casing being connected to the support so that the pad will be moved up and down in the box 20 when the support is adjusted.

8. Apparatus for use in applying pressure to shoe bottoms comprising a pad of yielding material, a fixed box enclosing the heel end portion of the pad, a separate box enclosing and supporting 25 the forepart of the pad, said separate box being pivoted to the fixed heel end box, a support in the fixed box for the shank portion of the pad, mask plates extending over opposite sides of the shank portion of the pad and carried by the shank support, 30 means for adjusting the shank support heightwise of the fixed box, and means for adjusting the forepart box about its pivot.

9. Apparatus for use in applying pressure to shoe bottoms comprising a pad of yielding material, 35 a box enclosing the end portion of the pad, a support in said box for the heel portion of the pad, a shank support pivoted to said support for the heel portion, means for adjusting the support for the heel portion heightwise of the pad to vary 40 the longitudinal contour of the pad, a casing embracing the support for the heel portion of the pad and connected thereto so that the pad will be carried up and down when the support for the heel end is adjusted, and mask plates connected 45 to the shank support.

10. Apparatus for use in applying pressure to shoe bottoms comprising a pad of yielding material, a forepart box enclosing and supporting the forepart of the pad and pivoted about a fixed axis, 50 a box embracing the shank and heel portions of the pad, separate members in said last-mentioned box for supporting the shank and heel portions of the pad, the front end of the shank support being pivoted adjacent to the axis of the forepart box, 55 the rear end of the shank support being connected to the heel support for heightwise movement therewith, and means for raising and lowering the heel support relatively to the box for the heel portion of the pad.

11. Apparatus for use in applying pressure to shoe bottoms comprising a relatively thick pad of yielding material, means for supporting the forepart of the pad, means for supporting the shank part of the pad, means for adjusting the forepart support about a transverse axis located midway of the thickness of the pad, means for adjusting the shank support about a transverse axis located below the lower side of the pad, means for indicating to the operator the amount of adjustment given to the forepart support about its axis, and means for indicating to the operator the amount of adjustment given to the shank support about its axis.

12. Apparatus for use in applying pressure to 75

shoe bottoms comprising a relatively thick hollow pad containing a fixed quantity of liquid, a support for the forepart of the pad arranged for movement about a fixed transverse axis located 5 midway of the thickness of the pad and substantially under the ball line of a shoe placed on the pad, a support for the shank portion of the pad mounted for movement about a fixed axis beneath the pad, a support for the heel end of the 10 pad, means for adjusting the heel support heightwise to vary the position of the rear end of the pad, and a plate pivoted to the rear end of the shank support and connected to the heel support, said connection permitting relative movement 15 lengthwise of the plate between the heel support and pad.

13. Apparatus for use in applying pressure to shoe bottoms comprising a relatively thick hollow pad containing a fixed quantity of liquid, a support 20 for the forepart of the pad arranged for movement about a center located midway of the thickness of the pad and substantially under the ball line of a shoe placed on the pad, a support for the shank portion of the pad mounted for movement about a fixed axis located beneath the pad, a support for the heel end of the pad, means for adjusting the heel support heightwise to vary the position of the rear end of the pad, and connections between the shank support and the heel support which permit relative movement 25 lengthwise of the pad between the heel support and the shank support.

14. Apparatus for use in applying pressure to 30 shoe bottoms comprising a rubber vessel containing a fixed quantity of fluid, said vessel being so molded that its top surface corresponds to the longitudinal curvature of a shoe that is to have a heel of medium height, and a support for the 35 forepart of the rubber vessel, said support being mounted for adjustment about a fixed transverse axis located substantially under the ball line of a shoe located on the vessel and midway of the height of the vessel whereby movement of the 40 support about said center to vary the longitudinal contour of the vessel will equalize the compressive and tensional strains set up in the top and bottom walls of the vessel when bent about said axis to accommodate shoes that are to have high and 45 low heels.

15. Apparatus for use in applying pressure to 50 shoe bottoms comprising a relatively thick hollow pad containing a fixed quantity of liquid, a support for the forepart of the pad arranged for movement about a fixed axis located midway of

the thickness of the pad and substantially under the ball line of a shoe placed on the pad, a support for the shank portion of the pad mounted for movement about a fixed axis below the lower wall of the pad, a support for the heel end of the pad, means for adjusting the heel support heightwise to vary the position of the rear end of the pad, a plate pivoted to the rear end of the shank support and connected to the heel support, said connection permitting movement of the plate 10 lengthwise of the pad between the heel support and the pad, and means for adjusting the forepart support heightwise of the pad.

16. Apparatus for use in applying pressure to 15 shoe bottoms comprising a relatively thick hollow pad containing a fixed quantity of liquid, a support for the forepart of the pad arranged for movement about a fixed axis located midway of the thickness of the pad and substantially under the ball line of a shoe placed on the pad, a support for the shank portion of the pad mounted for movement about a fixed axis below the lower wall of the pad, a support for the heel end of the pad, means for adjusting the heel support heightwise to vary the position of the rear end of the pad, a plate pivoted to the rear end of the shank support and connected to the heel support, said connection permitting movement of the plate 20 lengthwise of the pad between the heel support and the pad, and means for adjusting the forepart support heightwise of the pad, and means for indicating to the operator the amount of each 25 adjustment.

17. Apparatus for use in applying pressure to 30 shoe bottoms comprising a rubber vessel containing a fixed quantity of fluid, said vessel being so molded that its top surface when the vessel is unstressed corresponds to the longitudinal curvature of the bottom of a shoe that is to have a heel 35 of medium height, supports for the shank and heel portions of the vessel, and a support for the forepart of the vessel, said support being mounted for adjustment about a fixed transverse axis located substantially under the ball line of a shoe 40 located on the vessel and midway of the height of the vessel whereby movement of the support about said center to vary the longitudinal contour of the vessel will equalize the compressive and tensional strains set up in the top and bottom 45 walls of the vessel when bent about said axis to accommodate shoes that are to have higher and lower heels than that for which the vessel was 50 molded.

ROYAL G. MADAN. 55
